UNITED STATES PATENT OFFICE.

GUSTAVE RADER, OF MONTCLAIR, NEW JERSEY.

MOLDING-TABLE FOR MAKING PLASTER-BOARDS.

No. 884,953.

Specification of Letters Patent.

Patented April 14, 1908.

Application filed December 26, 1907. Serial No. 408,016.

To all whom it may concern:

Be it known that I, GUSTAVE RADER, a citizen of the United States, residing in Montclair, in the county of Essex and State of New Jersey, have invented certain new and useful Improvements in Molding-Tables for Making Plaster-Boards, of which the following is a specification.

This invention relates to an improved molding table for making plaster boards of that kind in which the body of the plaster board is provided with a face-layer of paper, muslin or other fabric, said table being capable of making these plaster-boards in a quick and effective manner, and at a considerable saving in time and labor; and for this purpose the invention consists of a molding table for making plaster-boards which comprises a table, means for supplying a layer of paper or fabric over the entire length of the table, gage-bars guided along the sides of the table, means for locking the gage-bars at a certain height above the table according to the thickness of the plaster-boards to be made, and transverse dividing rods inserted in openings of the gage-bars for defining the length of the plaster-boards and permitting the convenient separation of the same.

The invention consists further of certain details of construction and combinations of parts which will be fully described herein-after and finally pointed out in the claims.

In the accompanying drawings, Figure 1 represents a perspective view of my improved molding table for making plaster-boards, Fig. 2 is a detail vertical transverse section on line 2, 2, Fig. 1, showing the connection of the gage-bars with the sides of the molding table, Fig. 3 is a side-elevation of an end-portion of the molding table, drawn on a larger scale, and Fig. 4 is an end-elevation of the table partly in section through the setting-lever of one of the gage-bars.

Fig. 5 is a detail showing means used to drive the rolls by which the paper is fed or supplied over the length of the table.

Similar letters of reference indicate corresponding parts throughout the several views.

Referring to the drawings, *a* represents a table which is equal in width to the width of the plaster-boards to be made, and of a length equal to the length of say five plaster-boards. At the rear-end of the table *a* are arranged journal-bearings for receiving a roll

r of paper, muslin or other fabric *p*, and adjacent thereto are supported on the table in suitable bearings two guide-rollers *b* through which the paper or other fabric *p* is guided until it is drawn out over the full length of the table for entirely covering the same. To opposite sides of the table and normally on a level with the surface of the table are arranged two gage-bars *d*, which are preferably made of wrought iron, and which are guided by inclined slots *d*¹, it may be friction tight, on headed screw-studs *d*² which are attached to the side-timbers of the table, washers *d*³ being interposed between the gage-bars *d* and the heads of the screw-studs *d*² so as to permit the free motion of the gage-bars along the sides of the table. The side-timbers of the table *a* are provided throughout their length with metallic plates *d*⁴ for reducing the friction of the gage-bars *d* with the side-timbers of the table and permitting the easy adjustment of the gage-bars on the side-timbers. The front-ends of the gage-bars *d* are extended beyond the front-end of the table *a* and connected by means of pivot-bolts *e*, that pass through holes in the gage-bars with slots *e*¹ in two handle-levers *f* which are pivoted at their lower ends to perforated ears *f*¹ attached to the lower parts of the front legs of the table, as shown clearly in Fig. 3.

At distances corresponding to the length of the plaster-boards are inserted into corresponding holes of the gage-bars *d* transverse rods *g*, of round or other cross-section, which are preferably tapered at one end and bent at right angles at the opposite end so as to form handles *g*¹. The pointed ends serve for facilitating the insertion of the rods *g*, while the bent ends *g*¹ serve as handles in passing the rods through the holes of the gage-bars and for turning the same on their axes after the plaster-boards are formed on the table.

Fig. 5, indicates a driving crank for rolls *b*.

The gage-bars *d* are raised by means of the hand-levers *f* along their guide-slots to such an extent that their upper edges are at such a height above the surface of the table as is required for the thickness of the plaster-boards to be made. The gage-bars *d* are then locked in the required position by pivot-hooks *h* on the hand-levers *f*, which hooks engage holes *h*¹ in flanged-plates *h*², attached to

the front-legs of the table *a*. The transverse separating rods *g* are then placed across the table through the holes in the gage-bars, as shown in Figs. 1 and 2. The plaster, which is mixed with hair, fibers or other fibrous strengthening material, is then spread over the paper or other fabric covering the surface of the table to the upper edges of the gage-bars and separating rods *g*, and carefully trimmed so as to form plaster-boards of uniform thickness. When the plaster-mass has partly set, the transverse separating rods are taken hold of at their handles and turned on their axes by means of their handle-ends *g*¹ so as to get loose from the partly-set mass of plaster. The separating rods are then removed. The plaster-mass is then permitted to harden. The gage bars are then lowered so as to expose the sides of the body of plaster. Then one plaster-board after the other is separated by bending it over and breaking the layer of paper or fabric at the points below the indentations formed by the separating rods, which is readily accomplished by bending up first one plaster-board and breaking the connecting fabric at the line of demarcation between the first and second plaster-board formed by the separating rod, after which the rod and the board are removed and so on, breaking off one plaster-board after the other, until all the plaster-boards are removed from the table.

The finished plaster-boards are then piled up and are used directly with the face-layer of paper or fabric on the same. The plaster-boards are of uniform thickness and of considerable strength, as not only the face-layer of paper or fabric reinforces the same, but also the hair or fibers that are mixed with the plaster-mass. By means of the vertical adjustable gage-bars any thickness of plaster board can be made. The plaster-boards are made in normal size of 30 by 36 inches. When longer plaster-boards are to be made, then the distance between the separating rods has to be made correspondingly longer.

The advantages of my improved molding table for making plaster-boards are, first, that a number of plaster-boards can be made at one operation, so that the expense of the same is reduced; second, that the molding table requires no cleaning after each operation as the face-layer of paper or fabric over which the plaster-mass is spread, keeps the table perfectly clean, and immediately ready for the next operation, whereby considerable time is saved as compared with the molding tables for single plaster-boards heretofore in use; and, third, that the plaster-boards made on the improved molding table do not require any trimming or finishing operation, but can be used directly as they come from the molding table.

Having thus described my invention, I

claim as new and desire to secure by Letters Patent:

1. A molding table for making plaster-boards, consisting of a table of sufficient length for making a plurality of plaster-boards, gage-bars at opposite sides of the table, means for adjusting the gage-bars to project to the required degree above the surface of the table, means for supplying a surface-layer of paper over the full length of the table, and transverse separating rods inserted at uniform distances from each other into the upper portions of the gage-bars.

2. A molding table for making plaster-boards, consisting of a table of sufficient length for making a plurality of plaster-boards, gage-bars located at opposite sides of the table, means for guiding the gage-bars along the sides of the table, means connected with the gage-bars for adjusting the gage-bars lower or higher relatively to the surface of the table, and transverse separating rods passing through holes in the upper portions of the gage-bars.

3. A molding table for making plaster-boards, consisting of a table of sufficient length for making a plurality of plaster-boards, gage-bars located at the sides of the table, means for raising or lowering the gage-bars along the sides of the table relatively to the surface of the same, means for locking the gage-bars after adjustment, and transverse separating rods supported by said gage-bars.

4. The combination, with a table of sufficient length for making a plurality of plaster-boards, of gage-bars provided with inclined slots, headed studs attached to the upper side-portions of the table for guiding the gage-bars, levers pivoted to the projecting ends of the gage-bars and the front-legs of the table, means for supplying a sheet of paper over the full length of the table, and transverse separating rods passing through holes in the upper portions of the gage-bars.

5. The combination, with a table of sufficient length for making a plurality of plaster-boards thereon, of a paper roll supported in bearings at the rear-end of the table for supplying a layer of paper or fabric over the full length of the table, gage-bars along the sides of the table, means for guiding the gage-bars along the sides of the table, means applied to the front-end of the table and the projecting ends of the gage-bars for adjusting them higher or lower along the guiding means to project a certain distance above the table, means for locking the gage-bars after adjustment, and transverse separating rods inserted at certain distances from each other in holes in the upper portions of the gage-bars.

6. In a molding table for making plaster-boards, the combination, with a table, of gage-bars extending along opposite sides of the table, pins and inclined slots connecting

the gage bars to the table and lever-operated means to adjust the gage-bars vertically.

7. In a molding-table for making plasterboards, the combination, with a table, of 5 vertically adjustable gage-bars at opposite sides thereof, and transverse separating rods extending between said gage-bars.

8. In a molding table for making plasterboards, the combination, with a table, of 10 gage-bars extending along the table at opposite sides, means to guide said gage-bars in inclined direction along the table-sides, and means for moving said gage-bars along said guiding means.

15 9. In a molding-table, the combination, with the table, of gage-bars extending along the sides thereof, means for guiding the gage-bars, means for adjusting them vertically, and transverse separating rods connecting 20 the gage-bars.

10. In a molding table, the combination, with the table, of a gage-bar extending along one side of the table and having an inclined slot, a headed stud engaged by said slot and 25 attached to the side of the table, and means for adjusting said gage-bar.

11. In a molding table, the combination, with the table, of a gage-bar extending along one side of the table and having an inclined 30 slot, a headed stud engaged by said slot and attached to the side of the table, and a pivoted adjusting lever connected with the end of said gage-bar.

12. In a molding table, the combination, 35 with the table proper, of gage-bars extending along opposite sides of the table and provided

with inclined slots, studs on the table-sides entering said slots, and adjusting levers connected with said gage-bars.

13. In a molding table for making plasterboards, the combination with a table, of 40 gage-bars extending along opposite sides of the table, means for adjusting the gage-bars to project to the required degree above the surface of the table and means for spreading 45 a layer of fabric over the surface of the table for separating the table from the plaster-mass.

14. In a molding table for making plasterboards, the combination, with a table, of 50 gage-bars extending along opposite sides of the table, means for adjusting the gage-bars to project to the required degree above the surface of the table, means for spreading a layer of fabric over the surface of the table, 55 and transverse separating rods extending between said gage-bars.

15. In a molding table for making plasterboards, the combination with a table, of 60 gage-bars extending along and past the opposite sides of the table, slots in said bars, and headed pins passing through said slots and tapped into the table and holding said bars in friction-tight adjustable engagement with the edge of the table.

In testimony, that I claim the foregoing as my invention, I have signed my name in presence of two subscribing witnesses.

GUSTAVE RADER.
